UNITED STATES PATENT OFFICE.

THOMAS R. BROWN, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC ELECTRIC TRAIN-LINE COUPLING.

Application filed July 5, 1918. Serial No. 243,495.

To all whom it may concern:

Be it known that I, THOMAS R. BROWN, of Pittsburgh, in the county of Allegheny and State of Pennsylvania, have invented 5 a certain new and useful Improvement in Automatic Electric Train-Line Couplings, of which improvement the following is a specification.

This invention relates to appliances for 10 coupling electric circuits between the cars of a train and more particularly to devices of this character in which each counterpart coupler is provided with a movable portion, or carrier for the electric contacts, adapted 15 to be projected out at the end of the car for making electric connection with the circuits of the adjoining car, and to be withdrawn or retracted when it is desired to disconnect and separate the cars.

20 The object of my invention is to provide a simple mechanical connection for positively projecting the movable portion of the electric coupler automatically, upon the coming together of the couplers, and it comprising together of the couplers, and it coming 25 comprises a tappet member yieldingly mounted in the coupler and adapted to engage a fixed portion of the counterpart coupler so as to be depressed thereby during the movement of said coupler in the coming together of 30 the cars, and a mechanical connection from said tappet for actuating the movable portion of the electric coupler to project the same and establish the desired electrical connection through the corresponding circuits between the cars.

35 In the accompanying drawing, Figure 1 is a side elevation, illustrating one form of electric coupler embodying my improvement; Fig. 2, a plan of the same, a portion 40 of the cover being broken away; Fig. 3 a detail transverse section taken on the line 3-3 of Fig. 2; Fig. 4, a detail view in plan showing the operating levers in normal uncoupled position; Fig. 5 a similar view 45 showing the coupled position; Fig. 6, a side elevation of the same; Fig. 7 a side elevation taken from the opposite side; and Fig. 8, a similar view showing the contacts in the extended position with the shutter open.

According to the construction shown the 50 electric coupler comprises a casing 10, adapted to be suspended at the end of the car, preferably beneath the car coupler, as indicated by dotted lines in Fig. 1, and containing a movable member or carrier 11, 55 for the electric contacts 12, connected to the respective train line circuits by wires 13. The contact carrier may preferably be mounted to slide upon suitable guides within the casing, and is adapted to be projected 60 out of the open front end thereof when it is desired to establish electrical connection through the circuits between the cars. In the design shown each electric line or wire 13 is divided into two branches connected to 65 a pair of contacts 12, one at each side of the vertical center line and adapted to make butt contact with the corresponding pairs of contacts of a counterpart coupler when the contact carriers 11 of the two couplers 70 are projected together.

75 For the purpose of projecting these contact carriers automatically by the coming together of the couplers of adjoining cars, I provide a yielding member or tappet 14, which may be mounted in any suitable manner and have mechanical connections for projecting the contact carrier. According to the particular construction shown the tappet member 14 is in the form of a short 80 lever mounted on a pivot 15, in the casing and normally extending out beyond the face thereof so as to engage with a fixed portion of the casing of a counterpart coupler and be depressed thereby when the two couplers 85 are brought together in the act of coupling the cars.

90 While various forms of mechanical connections actuated by the tappet member may be employed for projecting the contact carrier, there is shown an actuating lever 16 mounted on the pivot pin 17 within the casing below the contact carrier and carrying a stud 18, extending up within a slot 19 in said carrier. The tappet lever 14, has an 95 end portion 14^a, connected to the end portion 16^a, of the main lever though a link or ball 20, and a spring 21, with a rod 22,

is employed for opposing the outward movement of the lever on its pivot and for returning the same and the contact carrier to the normal or retracted position when the couplings are separated.

For protecting the contact terminals 12, from exposure to weather conditions, dust and dirt, when the couplers are separated, there is a shutter 23, having side arms 23^a, mounted on pivot pins 24, and adapted to swing over the opening at the front end of the casing. For automatically operating the shutter the lever 16, is provided with a lug or flange 25, at one end adapted to cooperate with a lug 26, on one of the arms 23^a, of the shutter and swing the same upward and away from the front opening.

In order that the electric contact terminals may be disconnected and withdrawn, in case it should be desired to do so, without uncoupling or separating the car couplers, means are provided for moving the fulcrum of the lever 16. For this purpose the pin 17, is carried by an arm 27, mounted to slide in guides 28, on the casing, but normally held in a fixed position against the side of the casing and a bracket 29, by means of a spring 30. A portion of the bracket 29, is cut away at 34, and a cam 31, with a shaft 32, and handle 33 comprises a means for manually shifting the arm 27, on its pivot 17, so that the end of the arm may slip into the recessed portion 34, of the bracket 29. A roller 35, mounted on the arm 27, may be employed to facilitate this action. When the couplers are coupled together and the handle 33, is turned to trip off the arm 27, it will be seen that the force of the tappet pressing upon the lever 16, will carry said lever backward and withdraw the contact carrier 11, toward its retracted position, the arm 27, sliding in the guides 28 on the casing. The cam 31 holds the arm 27, against the pressure of the spring 30, but when the cam is released by turning the handle 33, back to normal position, the spring 30, acts to push the roller up the inclined surface of the bracket and restore the arm 27, and fulcrum 17, of lever 16, to the normal position.

When two counterpart couplers are brought together in the act of coupling adjoining cars the tappet member of each coupler is engaged by a fixed portion of the counterpart coupler at the last part of the movement of the couplers in approaching each other, thereby depressing the tappet and turning the lever 16 upon its fulcrum 17. In the first part of this movement the lug or flange 25 at the end of lever 16, operates to swing the shutter upward to its open position, as indicated in Fig. 8, and the flat surface of the lug 26 then rests upon the top of the flange 25, which slides thereunder during its further movement. Dur-

ing this preliminary movement the stud 18, travels freely in the slot 19, in the contact carrier 11, without moving the same but upon the further and complete movement of the lever 16, due to the further movement of the tappet, the stud 18 engages the carrier and projects the same forward to its extended position, shown in Fig. 5 in which the contact terminals 12 make butt contact with the terminals of the counterpart coupler and establish electrical connection through the respective train line circuits. When the car couplers are uncoupled and pulled apart the spring 21, operates to return the lever 16 to its normal position, first moving the stud 18, through the slot 19, then withdrawing the contact carrier sufficiently to permit the shutter to close and then permitting said shutter to fall and completing the return movement of the contact carrier as the tappet member 14 is again extended out beyond the face of the casing.

What I claim is:

1. In an electric train line coupling, the combination of a pair of counterpart couplers each comprising a casing, a carrier movably mounted in said casing, a plurality of car line circuit contacts mounted on said carrier and engaging the corresponding contacts of the counterpart coupler when coupled together, yielding tappets each adapted to engage the other counterpart coupler, and mechanical connections operated by the movement of the tappets for projecting both of said contact carriers together.

2. In an electric train line coupling, the combination of a pair of counterpart couplers each comprising a casing, a carrier movably mounted in said casing, a plurality of car line circuit contacts mounted on said carrier and engaging the corresponding contacts of the counterpart coupler when coupled together, yielding tappets each adapted to engage the other counterpart coupler, mechanical connections operated by the movement of the tappets for projecting both of said contact carriers together at the same time, and springs for retracting said carriers when the couplers are separated.

3. In an electric train line coupling, the combination of a pair of counterpart couplers each comprising a casing, a carrier movably mounted in said casing, a plurality of car line circuit contacts mounted on said carrier and engaging the corresponding contacts of the counterpart coupler when coupled together, yielding tappets each adapted to engage the other counterpart coupler, and levers actuated by said tappets for projecting both of said contact carriers together at the same time.

4. In an electric train line coupling, the combination of a pair of counterpart couplers each comprising a casing, a carrier

movably mounted in said casing, a plurality of car line circuit contacts mounted on said carrier and engaging the corresponding contacts of the counterpart coupler when coupled together, yielding tappets each adapted to engage the other counterpart coupler, levers actuated by said tappets for project-

ing both of said contact carriers together at the same time, and springs for retracting said levers. 10

In testimony whereof I have hereunto set my hand.

THOMAS R. BROWN.
